UNITED STATES PATENT OFFICE

WILLIAM B. HILBERT, OF WAUKEGAN, ILLINOIS

ENVELOPE

Application filed February 16, 1929. Serial No. 340,539.

This invention relates to improvements in paper containers and deals more specifically with containers of the envelope type.

The primary object of the invention is to provide a novel form of envelope container having new and improved means for sealing or closing the envelope.

A further object of the invention is to provide an envelope having a sealing flap formed with a tongue which is insertable into the envelope and is held by a gripping device for preventing the opening of the envelope without destroying the sealing tongue.

Other objects and advantages of the invention will be apparent during the course of the following description.

In the accompanying drawings forming a part of this specification and in which like numerals are employed to designate like parts throughout the same,

Figure 1 is a perspective view of the envelope container embodying this invention and illustrated with the various end and side flaps positioned in readiness to receive a letter, or the like;

Figure 2 is a perspective view of a sheet carrying a fastening device;

Figure 3 is a plan view of the envelope entirely closed and sealed;

Figure 4 is a longitudinal sectional view of the envelope and taken upon line 4—4 of Figure 3;

Figure 5 is a transverse sectional view taken upon line 5—5 of Figure 3.

In the drawings, wherein for the purpose of illustration is shown a preferred embodiment of this invention, the numeral 6 designates the body portion of the container and this body portion may be either square or rectangular. In the present embodiment of the invention, said body portion is illustrated as being of rectangular formation. The ends 7 of the body portion 6 have formed integral therewith, or suitably connected thereto, end flaps 8 and 9 which are foldable upon lines of connection with the body portion to permit the flaps to overlie the body portion and partly overlap each other. The side edge 10 of the body portion 6 has secured thereto, a side flap 11 which is foldable upon the line

of connection between the flap and the body portion so that the side flap may overlie and partially overlap the end flaps 8 and 9 when the latter are folded over the body portion. Figs. 3 to 5 inclusive illustrate the manner in which the various flaps are foldable to overlie the body portion and to form a container with one side edge open. The various flaps 8, 9 and 11 are formed with slits 12, 13, and 14 respectively which register one with the other when the flaps are folded down upon the body portion. The slit 14 preferably is narrower than the slits 12 and 13 and the reason for this will be explained at a later point.

The edge 15 of the body portion 6 has suitably secured thereto a sealing flap 16 having suitably connected to its free edge an elongated sealing tongue 17. In closing the entrance to the envelope, the sealing flap 16 is folded over the previously folded flaps 8, 9 and 11 and the tongue 17 is inserted through the slit 14 and then through the slits 12 and 13 so that the said tongue then will be housed within the envelope and its extremity 17a will closely approach the side 10 of the body portion.

The slit 14 has been made of sufficient width to just receive the sealing tongue 17. In view of the fact that the slits 12 and 13 are concealed beneath the flap 11, these slits 12 and 13 must be made of sufficient width to enable the tongue 17 to readily pass through the same and to have free movement within the slits 12 and 13 so that the tongue will automatically move transversely of the interior of the envelope when it is fed through the various slits. Fig. 5 discloses the manner in which the tongue is permitted to move relative to the longitudinal edges of the slits 12 and 13 when the tongue is inserted into the envelope.

Fig. 2 discloses a sheet 18 which may be the letter or it may be a specially prepared sheet. This element 18 is cut along the inwardly converging lines 19 to form a foldable reinforcing piece 20. A metallic fastening device designated in its entirety by the reference character 21 is fastened to the sheet 18 in the manner best illustrated in Figs. 2 and 5. This fastening device includes a

100

main portion 22 having an upwardly and inwardly bent end portion 23, which is formed with a pointed extremity adapted to pierce the reinforcing piece 20 for anchoring the 5 fastening device to said piece. It will be seen that the angularly bent end portion 23 has been passed through the sheet 18 at the free edge of the reinforcing piece 20. The remainder of the fastening device consists 10 of a longitudinally extending portion 24 having an inwardly bent end 25 which is preferably sharpened at its extremity. When the sheet 18 is positioned within the envelope, the longitudinally extending portion 24 is 15 angularly arranged with respect to the main portion 22 so that the extremity 17^a of the sealing tongue 17 may pass into the space between the sharpened end portion 25 of the fastening device and the exposed face of the 20 reinforcing piece 20. After the sealing tongue has been inserted into the envelope and the extremity 17^a has been positioned in the manner just described, pressure upon the outside of the envelope directly over the 25 longitudinally extending portion 24 of the fastening device will cause this portion to be bent downwardly toward the main part 22 to cause the sharpened end 25 to pierce the sealing tongue 17 whereby this tongue 30 will be gripped and positively locked against withdrawal from the envelope.

It is to be understood that when a person desires to open the envelope, the sealing tongue 17 may be severed at a point between 35 its connection with the sealing flap 16 and the slit 14 or the tongue may be pulled out to cause it to tear loose from the fastening device 21 or to cause the fastening device to pull free from the sheet 18. It further is 40 to be understood that an adhesive may be applied to desired portions of the flaps 8, 9, 11 and 16 for interconnecting these flaps independently of the tongue 17 if the manufacturer so desires.

45 It is noted that the form of the invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. A paper container including a body portion, end and side flaps carried by the body portion, said flaps having slits which register when the flaps are folded over the body portion, a separate sheet having a reinforced edge with a fastening device secured 55 to the reinforced edge housed between the body portion and the folded flaps, and a closing flap having a sealing tongue insertable through said slits to engage and be held by the fastening device.
- 60 2. A paper container including a body

portion, end and side flaps carried by the body portion, said flaps having slits which register when the flaps are folded over the body portion, a sheet having a reinforcing piece cut therefrom and folded thereupon housed between the body portion and the folded flaps, a bendable gripping device anchored to the body of the sheet and the reinforcing piece and a closing flap having a sealing tongue insertable through said slits to engage and be held by the device when the latter is bent to grip the tongue.

3. A paper container including a body portion, end and side flaps carried by the body portion and having registering slots 70 when the flaps are folded over the body portion, a separate letter sheet to be housed within the container between the body portion and the folded flaps, said sheet having a reinforcing piece partly cut from one edge 75 and folded back over the body of the sheet to leave a notch in said edge, an angular fastening device having one part thereof passing through the sheet at the edge of said reinforcing piece and bent to pierce the piece 80 for anchorage thereto, the second part of said device passing around the sheet through the notch and having a sharpened extremity, and a closing flap having a sealing tongue 85 insertable through said slits to be pierced 90 by the sharpened extremity of said fastening device when the second part of the device is bent into engagement with the sealing tongue.

In testimony whereof I affix my signature.

WILLIAM B. HILBERT.
